UNITED STATES PATENT OFFICE.

ERNEST SCHILDBACK, OF ELMHURST, ILLINOIS.

WIND-SHIELD FOR VEHICLES.

No. 861,678.

Specification of Letters Patent.

Patented July 30, 1907.

Application filed March 13, 1907. Serial No. 362,178.

To all whom it may concern:

Be it known that I, ERNEST SCHILDBACK, a citizen of the United States, and a resident of Elmhurst, in the county of Cook and State of Illinois, have invented 5 certain new and useful Improvements in Wind-Shields for Vehicles, of which the following is a full, clear, and exact description.

My invention relates to wind-shields for vehicles, and particularly automobiles, and its object is to provide a divided or "split" transparent shield, the upper sash of which is readily removable from the top of the lower sash, and which can be easily and securely clamped into place either in a raised or lowered adjusted position. This I accomplish in the manner 10 hereinafter fully described and as more particularly pointed out in the claims.

In the drawings:—Figure 1 is a side elevation of my improved wind-shield shown applied to the forward portion of an automobile body, with the upper sash 20 in a raised position. Fig. 2 is a detached perspective view of the fixture for adjusting the upper sash. Fig. 3 is a transverse sectional view, slightly enlarged, taken on dotted line 3—3, Fig. 1. Fig. 4 is a similar view on dotted line 4—4, Fig. 1.

25 The drawings represent the forward portion of the body of an automobile comprising the usual side-sills A of the chassis and the hood B covering the driving or propelling mechanism of the vehicle. Secured to and arising above the dash-board at the rear of the hood is 30 the rectangular frame or lower sash C of the shield that surrounds a suitable plate of glass or other transparent material. This sash is preferably made of metal and its side edges project downwardly to provide suitable extensions c, c, that assist in securing the said lower 35 sash in place. Preferably mounted in the same vertical plane with and above the lower sash, and held in proper position by brackets D, is an upper removable sash d, which likewise consists of a rectangular metal frame surrounding a plate of glass and preferably corresponding 40 in dimensions and general outline with the lower sash.

As shown, brackets D are permanently secured to the edge of and project above the top of the stiles of the lower sash. They are each provided upon the vertical 45 faces opposite each other with a suitable U-shaped channel E, in which the upper sash preferably slides and is secured when adjusted in a raised position. In the upper outside edge of this bracket a suitable slotted recess e is cut away so as to seat the shank of a set-screw 50 F engaging a screw-threaded opening in the lower side edge of the upper sash, by the turning of which said sash is securely clamped in position. Cast integral with bracket D, and projecting outwardly preferably transverse to the vertical plane of the sashes, is a suitable 55 bifurcated bracing arm the two members of which merge into a socket f that is adapted to receive and

hold the upper end of a brace or stay-rod G. The opposite or lower end of this brace G preferably extends to and is bolted or otherwise secured to the forward portion of the side sills of the chassis.

60

At a convenient place upon the lower portion of the stiles of the lower sash I secure two laterally projecting supporting-plates H having their top edges each provided with a suitable recess or slot and it is so arranged that it is adapted to receive and support the upper sash 65 when the shield is lowered in the manner shown in dotted lines in Fig. 1. Secured to the upper portion of this sash is a plate having a keystone-shaped lug h projecting outwardly therefrom, the edges of which are undercut in the manner shown and are adapted to 70 engage a slot cut in boss i that is cast on the rear of the bracket D. When this wind-shield is in an open position the lower side edges of the stiles of the upper sashes are slid into the channel of bracket D until the 75 two sashes meet, and set-screw F is seated in the recess e. The milled head of the set-screw is then turned until it securely clamps the sashes in said bracket.

When it is desired to lower or close the wind-shield the upper sash is simply removed from above the lower sash and the lug h inserted in the slot in boss i on the 80 bracket. The sash may then be forced down as far as it will go in this slot so that the shank of screw F will seat itself in the recess of bracket H. The screw is then tightened until it clamps the parts securely in place so that they will not rattle or be jarred out of position 85 when the automobile is traveling over a rough roadway.

What I claim as new is:—

1. A wind-shield for vehicles comprising a stationary lower sash and an upper sash removably mounted thereon, means secured to and projecting above the stiles of said lower sash having channels in the inner opposing edges of their projected portions in which said upper sash is mounted, and provided with slotted recesses in one of the faces thereof, means engaging said upper sash and adapted to clamp the same to said first mentioned means in a vertical position above said lower sash, and means projecting from the upper portion of said upper sash and adapted to engage said slotted recess when the upper sash is lowered.

90

2. A wind-shield for vehicles comprising a stationary lower sash and an upper sash removably mounted thereon, means secured to and projecting above the stiles of said lower sash having channels in the inner opposing edges of their projected portions in which said upper sash is mounted, and provided with slotted recesses in one of the faces thereof, a set-screw engaging said upper sash and adapted to clamp the same to said means in a vertical position above said lower sash, and means projecting from the upper portion of said upper sash and adapted to engage said slotted recess when the upper sash is lowered.

95

3. A wind-shield for vehicles comprising a stationary lower sash and an upper sash removably mounted thereon, brackets secured to and projecting above the stiles of said lower sash having channels in the inner opposing edges of their projected portions in which said upper sash is mounted and provided with slotted recesses in one of the faces thereof, a set-screw engaging said upper sash and adapted 115

- 2
- to clamp the same to said bracket in a vertical position above said lower sash, and means projecting from the upper portion of said upper sash and adapted to engage said slotted recess when the upper sash is lowered. 5
4. A wind-shield for vehicles comprising a stationary lower sash and an upper sash removably mounted thereon, brackets secured to and projecting above the stiles of said lower sash having channels in the inner opposing edges of their projected portions in which said upper sash is mounted, and provided with slotted recesses in one of the faces thereof a set-screw engaging said upper sash and adapted to clamp the same to said bracket in a vertical position above said lower sash, a lug projecting from the upper sash and adapted to engage said slotted recess when the upper sash is lowered, and means secured to the lower portion of said lower sash for supporting said upper sash in a lowered position. 10
5. A wind-shield for vehicles comprising a stationary lower sash and an upper sash removably mounted thereon, brackets secured to and projecting above the stiles of said lower sash having channels in the inner opposing edges of their projected portions in which said upper sash is mounted, and provided with slotted recesses in one of the faces thereof, a set-screw engaging said upper sash and adapted to clamp the same to said bracket in a vertical position above said lower sash a lug projecting from the upper sash and adapted to engage said slotted recess when the upper sash is lowered, and a supporting-plate secured to the lower portion of said lower sash for supporting said upper sash in a lowered position. 15
6. A wind-shield for vehicles comprising a stationary lower sash, and a removable upper sash, brackets provided with slotted recesses, secured to and projecting above the stiles of said lower sash and having channels in the inner opposing edges of their projected portions in which said upper sash is mounted, a set-screw engaging said upper sash and adapted to clamp the same to said bracket above the lower sash, and lugs secured to and projecting from the upper portion of said upper sash adapted to engage the recesses in said bracket when said sash is lowered. 20
7. A wind-shield for vehicles comprising a stationary lower sash, and a removable upper sash, corresponding brackets secured to and projecting above the stiles of the lower sash and each consisting of a suitable plate provided with a slotted recess, a channel in the inner opposing edge of the projected portion of said plate, a cut away portion at the top of said channel and a bracing arm projecting forwardly from said plate, a set-screw engaging the upper sash and seated in said cut away portion and adapted to clamp said sash to said bracket, lugs projecting from said upper sash adapted to engage said recesses when lowered, and braces secured at one end to said bracing arm and having its opposite end secured to the body of the vehicle. 25

In testimony whereof I have hereunto set my hand and seal this 28th day of February, A. D., 1907.

ERNEST SCHILDBACK. [L. S.]
